CLAIM

(21) Appl. No.: **29/838,526**

The ornamental design for a respiratory physiotherapy trainer device, as shown and described.

(22) Filed: **May 13, 2022**

DESCRIPTION

(51) LOC (14) Cl. **24-02**

FIG. 1 is a front perspective view of a respiratory physiotherapy trainer device, showing my new design.

(52) U.S. Cl.

FIG. 2 is a front view of the respiratory physiotherapy trainer device of FIG. 1.

USPC **D24/129**

FIG. 3 is a rear view of the respiratory physiotherapy trainer device of FIG. 1.

(58) **Field of Classification Search**

FIG. 4 is a right side view of the respiratory physiotherapy trainer device of FIG. 1.

USPC D24/108, 110, 110.1–110.6, 112, 127,
D24/129, 133
CPC A61M 16/06; A61M 16/0616; A61M
16/0622; A61M 16/0633; A61M 16/0683;
A61M 16/08; A61M 16/0816; A61M
16/0825; A61M 16/0833; A63B 23/18;
A63B 23/185

FIG. 5 is a left side view of the respiratory physiotherapy trainer device of FIG. 1.

See application file for complete search history.

FIG. 6 is a top view of the respiratory physiotherapy trainer device of FIG. 1; and,

(56) **References Cited**

FIG. 7 is a bottom view of the respiratory physiotherapy trainer device of FIG. 1.
